UNITED STATES PATENT OFFICE.

PAUL MACGAHAN, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRICAL PROTECTIVE DEVICE.

1,314,825.

Specification of Letters Patent.

Patented Sept. 2, 1919.

Application filed February 10, 1916. Serial No. 77,389.

To all whom it may concern:

Be it known that I, PAUL MACGAHAN, a citizen of the United States, and a resident of Pittsburgh, in the county of Allegheny and State of Pennsylvania, have invented a new and useful Improvement in Electrical Protective Devices, of which the following is a specification.

My invention relates to electrical-protective devices and particularly to relays and relay systems that are employed for tripping circuit interrupters, or operating other devices, upon the occurrence of predetermined conditions.

One object of my invention is to provide a relay system of the above indicated character that is adapted to trip a circuit interrupter when the energy and current traversing it are reversed and of a predetermined value, respectively.

Another object of my invention is to provide a reverse-energy relay for a system of the above indicated character that is disproportionately more responsive to low values of voltage than to high values of voltage.

Another object of my invention is to provide a reverse-energy relay having two relatively movable windings that are so disposed with respect to each other that one will not induce voltage in the other, and, consequently, the phase-angular relation of their voltages will not be displaced.

Another object of my invention is to provide a relay having a movable member that will not be attracted by the magnetizable core member of the relay, and, consequently, will not vibrate at relatively high loads.

Another object of my invention is to provide a reverse-energy relay having an unrestrained movable member that is adapted to move freely upon the application of a minimum force in either direction.

In the carrying out of my invention, I provide a relay system that comprises a reverse-energy relay, a current relay and two series-connected switches which are adapted to be actuated by the respective relays for controlling the tripping of a circuit interrupter. The windings of the reverse-energy relay are so disposed with respect to each other that one does not induce a current in the other thus preventing the operation of the relay when current traverses one winding and not the other. A normally incan-

descent tungsten lamp is connected in circuit with the potential winding of the reverse-energy relay to cause it to be disproportionately more responsive to low values of voltage than to high values of voltage. 60 The movable member of the reverse-energy relay is so unrestrained that it is adapted to move freely upon the application of a minimum force in either direction, thus securing effective operation when a short circuit or other disturbance on the system causes its voltage to decrease. The armature of the reverse-energy relay is not a conducting disk, as is the case in the ordinary reverse-energy relay of the induction type, 70 and, consequently, the vibration caused by the attraction of the armature to the magnetizable core member at relatively high loads is precluded.

In the accompanying drawings, Figure 75 1 is a front elevational view of a combined reverse-energy relay and current-relay device embodying my invention; Fig. 2 is a side view, partially in elevation and partially in section, of the relay device shown 80 in Fig. 1; Fig. 3 is a top view, partially in plan and partially in section, of the relay device shown in Figs. 1 and 2; Figs. 4 and 5 are diagrammatic elevational and plan views, respectively, of the reverse-energy 85 relay shown in Figs. 1, 2 and 3, and Fig. 6 is a diagrammatic view of a part of the relay system embodying my invention.

A typical system, in connection with which my present invention may be employed, comprises an alternating-current circuit 1 that is adapted to be interrupted by means of a circuit interrupter 2. The primary winding 3 of a current transformer 4 is connected in series relation with one conductor of the circuit 1, and its secondary winding 5 is connected in a circuit comprising the windings 6, 7, 8 and 9 of a reverse-energy relay 10 and the winding 11 of a current relay 12. The primary winding 13 90 of a potential transformer 14 is connected in parallel relation to the conductors of the circuit 1 and its secondary winding 15 is connected in circuit with the potential winding 16 of the relay 10 and a normally 100 incandescent tungsten lamp 17.

The relay 10 comprises two stationary magnetizable core members 18 and 19 of substantially U-shape that are so disposed with respect to each other that their respec- 110

tive legs are adjacent but separated by air gaps 20 and 21. The windings 6, 7, 8 and 9 surround the legs of the core members 18 and 19, and they are so connected that 5 their magnetic fluxes are cumulative. The movable member of the relay 10 is mounted on a shaft 22 and comprises the winding 16 and a mutilated or segmental damping disk 23. A movable arm 24 is also mounted 10 on the shaft 22 and is adapted to actuate a movable contact member 25 that co-operates with a stationary contact member 26. The damping disk 23 is adapted to extend between the poles of damping magnets 27 15 but is not adapted to extend into the air gaps 20 and 21. The winding 16 is so normally disposed with respect to the windings 6, 7, 8 and 9 that no resultant current is induced therein, and, consequently, their 20 phase-angular relation will not be distorted.

The relay 12 comprises a magnetizable core member 28 having a central leg, two side portions that are spaced from the central leg at one end by air gaps and down- 25 wardly projecting portions that are spaced from the central leg by an air gap. The core member 28 may be constructed in accordance with the core member shown in copending application Serial No. 840,754, 30 filed by William M. Bradshaw, May 25, 1914, and assigned to the Westinghouse Electric and Manufacturing Company. The relay 12 is provided with a winding 29 that is connected to the primary winding 30 of 35 a normally saturable transformer 31, the secondary winding 32 of which is connected in circuit with the windings 33 that surround the downwardly extending portions of the magnetizable core member 28. A 40 conducting disk or armature 34 is mounted upon a shaft 35 and is adapted to extend within the air gap between the downwardly extending portions and the central leg of the magnetizable core member 28. A mov- 45 able arm 36 is also mounted upon the shaft 35 and is adapted to actuate a movable contact member 37 that engages a stationary contact member 38. The saturable transformer 31 is provided for controlling the 50 operation of the relay 12 and is so proportioned that the time element of operation of the relay shall be substantially inversely proportional to the current traversing the circuit 1 up to predetermined current values 55 and invariable or definite above these predetermined values, substantially as set forth in application Serial No. 771,888, filed by A. W. Copley and B. H. Smith, June 5, 1913, and assigned to the Westinghouse 60 Electric and Manufacturing Company.

The contact members 25, 26, 37 and 38 are series connected in a circuit comprising a tripping coil 39 and a source of electro-motive force 40. Since the movable arm 24 65 of the reverse-energy relay is adapted to

effect engagement of the contact members 25 and 26 when the energy reverses in the circuit 1, and, since the movable arm 36 of the relay 12 is adapted to effect engagement of the contact members 37 and 38 when the 70 current traversing the circuit 1 reaches a predetermined value, if these two conditions occur simultaneously, the winding 39 is adapted to be energized to trip the circuit interrupter 2. 75

The armature 34 of the relay 12 is adapted to extend between the poles of permanent damping magnets 41 for the purpose of retarding its movement, and an adjustable spring 42 is provided for adjusting the operation of the relay. 80

The relays 10 and 12 are mounted within a casing 43 that is provided with a face plate 44 for observing the operation of the devices. The casing 43 is provided with 85 legs and bolts for mounting the same on a switchboard or other suitable structure. However, my invention is not limited to the particular casing or form of mounting that is illustrated. 90

The conductors of the winding 16 are subjected to such fluxes from the windings 6, 7, 8 and 9 that no electromotive force is induced therein to distort the phase angle of the current that is supplied by the transformer 14. That is, one side of the winding lies directly in the field of the windings 6 and 9 and the other side lies in the field of the windings 7 and 8. Thus, since the flux that cuts one side of the winding is of opposite sign to that which cuts the other side, the resultant induced current in the winding 16 is zero. The movement of the winding 16 is very small, and, consequently, the windings are adapted to be so related under all 100 conditions of its movement that their resultant mutual inductance is relatively low. Thus, when a relatively large load traverses the circuit 1, such as under short-circuit conditions, the relay will function properly 110 as a reverse-energy relay, whereas, if the resultant mutual induction was not substantially zero, one winding would induce sufficient current in the other to cause it to operate on excessive loads in the normal direction. Further, since no disk is provided 115 between the magnetizable core members 18 and 19, no attraction of the movable member will obtain under short-circuit conditions, and the movable member will not vi- 120 brate. 125

Since the resistance of a tungsten filament increases with the temperature and varies almost instantaneously with the applied voltage, it will be seen that the lamp 17 will 125 tend to cause disproportionately more current to traverse the winding 16 when the voltage across the circuit 1 is low than when the voltage across the circuit 1 is high. This is advantageous when the voltage of a circuit 130

is reduced to a low value because of a short circuit or other disturbance. The movable member of the relay 10 is free to move in either direction. Hence, it will be more responsive to a reversal of the energy than it would be if it were provided with a control spring.

While I have shown my invention with respect to a particular structure, it will be understood that it is not so limited, but is adaptable to various modifications, as set forth in the appended claims.

I claim as my invention:

1. A relay system comprising unrestrained means freely responsive to the direction of flow of energy, independently movable means responsive to current, and electro-responsive means controlled by the simultaneous operations of the said means, said electro-responsive means being adapted to operate, only when the energy traversing the system is in the reverse of its normal direction and its current is of a predetermined value.
  2. In a protective device for an electric circuit, the combination with an electro-responsive device, of a reverse-energy relay, an independently movable over-current relay, and means actuated by the relays for controlling the operation of the electro-responsive device when the energy traversing the circuit is reversed and its current is of a predetermined value.
  3. A relay comprising a stationary magnetizable member having two pole-pieces, windings therefor, and a rotatable member having a winding thereon, said rotatable member being adapted to be normally in such position with respect to the pole-pieces, and the windings of the pole-pieces being so oppositely connected, that the resultant mutual inductance has a relatively low value.
  4. A relay comprising a stationary magnetizable member having two pole-pieces, oppositely connected windings for the pole-pieces, a rotatable member movable in a plane parallel to the face of the pole-pieces, and a winding disposed on the rotatable
- member in such position that, under normal conditions, the voltage induced therein by one pole of the magnetizable member is neutralized by that induced by the other pole.
5. A relay comprising a stationary magnetizable member having two pole-pieces, oppositely connected windings for the pole pieces, a rotatable member movable in a plane parallel to the face of the pole-pieces, and a winding disposed on the rotatable member in such position that, under normal conditions, the mutual inductance between the stationary and movable windings has a relatively low value.
  6. In an electric circuit, the combination with a circuit interrupter and a trip coil therefor, of two series-connected switches, a freely movable reverse-energy relay for operating one of the switches upon a reversal of energy, and a current relay for operating the other switch when the current traversing the circuit reaches a predetermined value.
  7. In an electric circuit, the combination with a freely movable reverse-energy relay, of a resistor connected in circuit with the potential winding of the reverse-energy relay for rendering it disproportionately more sensitive to relatively low voltages than to relatively high voltages.
  8. In an electric circuit, the combination with a freely movable reverse-energy relay, of an incandescent lamp connected in circuit with the potential winding of the relay for rendering it disproportionately more sensitive to relatively low voltages than to relatively high voltages.
  9. In an electric circuit, the combination with a reverse-energy relay, of a normally incandescent resistor connected in circuit with the potential winding of the relay for rendering it disproportionately more sensitive to relatively low voltages than to relatively high voltages.

In testimony whereof, I have hereunto subscribed my name this 31st day of Jan. 1916.

PAUL MacGAHAN.
